CUSHIONING DEVICE

Gust J. Christenson, Chicago, Ill.

Application February 25, 1944, Serial No. 523,951

3 Claims. (Cl. 267—9)

1

This invention relates to improvements in cushioning devices and it consists of the matters hereinafter described and more particularly pointed out in the appended claims.

One of the objects of the invention is to provide a spring and friction type of cushioning device which is of simple construction so as to be inexpensive to manufacture and will assure a long period of trouble-free operation.

Another object of the invention is to provide a cushioning device that includes a novel friction shoe having oppositely disposed wedging surfaces and which shoes may be placed in the assembly, either end first, and may be reversed end for end to provide a new wedging surface when the one first used becomes worn in service.

Also it is an object of the invention to provide a cushioning device of this kind so constructed as to reduce, if not entirely eliminate, breakage of the bolt that holds the parts of the device in assembled relation.

The above mentioned objects of the invention, as well as others, together with the advantages thereof will more fully appear as the specification proceeds.

In the drawing:

Fig. 1 is a vertical sectional view through a cushioning device embodying the preferred form of the invention.

Fig. 2 is a horizontal sectional view through the same as taken on the line 2—2 of Fig. 1.

Fig. 3 is a perspective view of one of a plurality of friction shoes embodied in the improved cushioning device.

Fig. 4 is a bottom plan view of a certain collar embodied in the improved cushioning device.

Referring now in detail to that embodiment of the invention illustrated in the drawings, the improved cushioning device includes a main spring 10. This spring is preferably formed from a length of square rod or bar stock, thus providing a cylinder having an external friction surface interrupted only by the spacing between the convolutions thereof. The endmost convolutions of the spring are ground to provide flat ends for the spring.

The flat ends of the spring 10 engage or abut against follower plates 11 and 12 respectively. These plates, which are counterparts, are of a diameter somewhat greater than that of the spring so that peripheral margin thereof extend outwardly from the periphery of the spring. Each plate is provided with a central hollow boss 13 of a diameter to enter the associated end of the spring 10 to keep the same centered

with reference to said plates. Each boss includes an apertured end wall 14. A headed bolt 15 passes through said apertured end wall of each plate to receive a nut 16 and retain the parts of the device in assembled relation. A spring 17 surrounds that part of the bolt between its head 18 and the end wall 14 of one of the plates 11—12 to absorb rebound shocks which might otherwise fracture the retaining bolt.

19—19 indicate a plurality of arcuate or partly cylindrical friction shoes, of a length less than that of the spring 10 when disposed between the follower plates 11 and 12. One of said shoes is shown in perspective in Fig. 3. These shoes, which are arranged in grouped relation about one end of the spring 10, each engages at one end with one of the plates 11—12. Each shoe has an internal friction surface 20 which conforms to the external friction face of the spring 10. When said shoes are arranged in the position they occupy in the device, they provide a split cylinder, the parts of which are capable of a limited movement radially with respect to spring.

25 Each shoe is provided on its external surface, midway between its ends with an outwardly projecting rib 21 having oppositely inclined wedge surfaces 22—22 respectively. With the shoes made as described, the ends of the shoes are reversible so that no particular care is required in arranging a particular end in a particular position in the assembly of the device.

23 indicates a rigid collar that surrounds one end of the shoes 19—19 and holds them together 35 operatively in grouped cylindrical position. This collar is provided at one end with a flat surface 24 that forms a spring seat, as will later appear and is provided at its other end with a bevelled surface 25 of the same inclination as the surfaces 22 of the shoes.

35 A spring 26 is so disposed in the assembly that it engages at one end upon the seat 24 of the collar 23 and abuts at its other end against the other of the plates 11—12. As best shown in 45 Fig. 1, the outside diameter of the rib 21 of the shoes and the outside diameter of the collar, approximate that of the follower plates so that a device of symmetrical shape is afforded.

When the device is subjected to a compressive 50 load action from either end, so that the follower plates approach each other, the spring 10 is placed under compression and tends slightly to increase in diameter. Likewise, as said follower plates approach each other, the spring 26 transmits load pressure to the collar 23 which,

through the surfaces 22 of the shoes engaged thereby, tends to move said shoes radially inwardly. In this movement of the shoes, the friction surfaces 20—20 thereof frictionally engage with the external surface of the spring 10 to gradually cushion the compression of said spring.

Upon release of the compression load, the spring 10 tends to expand axially and while the spring 26 will also tend to expand, it still retains stored energy which, operating through the collar 23 and surfaces 22 of the shoes, checks the sudden expansion of the spring 10. The bolt 15, operating through the follower plates 11 and 12, determines the amount of axial expansion of the spring 10 and as the limit thereof approaches, the spring 17 functions to cushion the action on the bolt so that shock sufficient to fracture the bolt is avoided.

Should the active surface 22 of the shoes become worn through use, to that condition requiring service, the device may be disassembled and the shoes reversed in position end for end in the reassembly of the device to provide a new active surface therefor.

The device presents no projecting external parts which may catch on parts of other devices with which it is associated in storage and shipment.

The device is of simple construction and is easy to assemble and is therefore relatively inexpensive to produce. It is positive, though smooth, in action and therefore is relatively noiseless.

While in describing the invention I have referred in detail to the form arrangement and construction of the parts employed, the same is to be considered only in the illustrative sense so that I do not wish to be limited thereto except as may be specifically set forth in the appended claims.

I claim as my invention:

1. A cushioning device embodying therein a helical spring having an external friction surface, a follower plate for each end of said spring, a plurality of friction shoes arranged externally of said spring and each engaged at one end with one of said follower plates, each shoe having an internal surface for engagement with the external friction surface of said spring and each shoe having an external tapered surface, and a second spring bearing at one end against the other

of said follower plates and at its other end exerting a pressure action upon said tapered surfaces of said shoes.

2. A cushioning device embodying therein a helical spring having an external friction surface, a follower plate for each end of said spring, a plurality of friction shoes arranged externally of said spring and each engaged at one end with one of said follower plates, each shoe having an internal surface for engagement with the external friction surface of said spring and each shoe having an external tapered surface, a collar surrounding portions of said shoes and having a surface formed for engagement with the tapered surfaces of said shoes, and a second spring bearing at one end against the other of said follower plates and at its other end bearing against said collar.

3. A cushioning device embodying therein a helical spring made of rectangular spring stock and providing an external friction surface, a follower plate for each end of the spring, a plurality of shoes each having an internal surface for engagement with the friction surface of said spring and each having a portion projecting from the external surface thereof and formed to provide oppositely tapering surfaces between the ends thereof so that either end of said shoes may be engaged with one of said follower plates, a collar surrounding portions of said shoes and having a surface for engagement with one of said tapered surfaces of all of said shoes, and a second spring bearing at one end against the other of said follower plates and bearing at its other end with said collar.

GUST J. CHRISTENSON.
